UNITED STATES PATENT OFFICE.

CHARLES E. SCRIBNER, OF CHICAGO, ILLINOIS, ASSIGNOR TO THE WESTERN ELECTRIC COMPANY, OF SAME PLACE.

TEST-CIRCUIT FOR MULTIPLE SWITCH-BOARDS.

SPECIFICATION forming part of Letters Patent No. 427,120, dated May 6, 1890.

Application filed December 27, 1886. Serial No. 222,698. (No model.)

To all whom it may concern:

Be it known that I, CHARLES E. SCRIBNER, a citizen of the United States, residing at Chicago, in the county of Cook and State of Illinois, have invented a certain new and useful Improvement in Test-Circuits for Multiple Switch-Boards, (Case 120,) of which the following is a full, clear, concise, and exact description, reference being had to the accompanying drawings, forming a part of this specification.

My invention relates to multiple switch-board systems of a telephone-exchange; and its object is to provide a uniform test whereby it may be determined at one board whether another line, whether single or metallic, is in use or connected at any other of the boards.

Heretofore many different test-circuits have been invented. The one most commonly in use is described and claimed in my patent, No. 305,021, of September 9, 1884. The system therein described is primarily designed for use in connection with ground-circuits. When metallic circuits are used, in order that there may be a uniform test for metallic circuits and ground-line circuits it has heretofore been thought necessary to employ special test-circuits, one for each metallic circuit as well as for each ground-circuit, with separate test pieces and connections upon the different boards.

By the use of my invention herein I am enabled to make the test the same, whether the line tested be a metallic circuit or a ground-circuit, and without the use of the additional or special test-circuits for the different telephone-lines, as heretofore, the spring-jacks which I use having preferably the same number of contact-points as those shown in my said patent.

A feature of my invention is a circuit-breaker, one circuit-breaker being included in each line between the contact-point on the spring-jack of the last board and the test piece or frame of said spring-jack. These circuit-breakers are driven constantly in any suitable manner, so that as long as no plug is inserted in any spring-jack of a line the circuit of said line will be continuously interrupted. On inserting a plug in a spring-jack of any line the portion of the line containing

the circuit-breaker will be left dead open at the spring-jack in which the plug is inserted, and thus the circuit-breaker will have no effect upon the line.

When metallic circuits are used, the branch or side of the circuit which connects with the frames or test-pieces of the switches of the line extends to the subscriber's station, and is there normally open. In case ground-circuits are used, the line is connected with the subscriber's outfit in the usual manner, and extends thence through the switches of the line and back to the test pieces or frames, and after passing through the test-pieces through resistance to ground. Metallic and ground circuits thus connected may be used as desired upon the same switch-boards. The individual annunciator is preferably placed next to the circuit-breaker in each line, so that it will come in the wire between the point of the last spring-jack and the frame or test piece of said spring-jack.

In my patent, No. 383,495, granted May 29, 1888, application for which was filed simultaneously with this, I have described and claimed an invention to enable operators at different boards to test to determine whether any line is busy when said lines are connected with ordinary spring-jack switches and without the use of special test-wires and special connections therefor.

In another application filed upon the same day, Serial No. 222,706, now pending, I have described an invention which consists, essentially, in placing a buzzer in circuit with the individual annunciator in each line in combination with circuits and testing apparatus, by means of which, when a test is made, the buzzer will cause a tone in the telephone if the line tested is free.

My invention will be readily understood by reference to the accompanying drawings, in which—

Figure 1 is a diagram illustrative of two telephone-lines—one metallic and the other ground—connected with two multiple switch-boards, each line including an intermittent circuit-breaker. Fig. 2 is a diagram showing the connections of the metallic circuit at a subscriber's station. Fig. 3 is a detail sectional view of the loop-plug which is used in

connection with the double-stranded cords of the key-board apparatus.

The metallic circuit is shown connected with the spring-jacks *a* and *b* upon the different boards in Fig. 1. The ground-circuit is shown connected with the spring-jacks *c* and *d* upon the different boards. It will be observed that the connections with spring-jacks *a* *b* are the same as the connections with spring-jacks *c* *d*, the only difference in the circuits being that the wire connecting with the frames of spring-jacks *a* *b* extends back to the subscriber's station, while the wire connected with the frames or test pieces of switches *c* *d* passes through resistance *e* at the central office to ground. The metallic circuit may be traced from ground *f* at the subscriber's station (see Fig. 2) through the generator and bell to the subscriber's switch *g*, and thence by branch *h* back to the subscriber's station (see Fig. 1) and through the spring-jacks *a* *b*, and from the point of the last spring-jack by wire *i* through the circuit-breaker *k* and the annunciator to branch *l*, which branch *l* is connected with the frames of the switches *a* *b* and extends to the subscriber's station, where said branch *l* is normally open. Branch *l* at the subscriber's station is connected through the telephone, and from the line side of the telephone there is a connection to a switch for closing branch *l* to ground when the subscriber sends current to line by turning his generator.

The ground-line *m* is connected, as shown, through the switches *c* *d*, and thence by wire *n* through the circuit-breaker *o* and the annunciator back to the frames of said switches *c* *d*, and through resistance *e* to ground at the subscriber's station.

It should be noted that branch *l* of the metallic circuit being open at the subscriber's station, its resistance will be infinite. The resistance *e*, however, in the test portion *n* of the ground-circuit is high enough, so that when a connection is made with the test-wire *n* at the frame of any spring-jack sufficient current will be shunted from line *m* through the telephone thus connected at the frame of any spring-jack of the line.

The key-board apparatus which I have shown forms the subject-matter of an application filed herewith, being my Case No. 119. I shall therefore describe the key-board apparatus only incidentally herein. It is evident that other key-board systems might be used successfully in connection with my test-circuits.

I will now describe the manner of testing to determine whether a line called for at the board is in use or connected at any other board.

It will be observed that the two telephone-lines are shown connected together at spring-jacks *b* *d* of the last board in Fig. 1. At the first board the tip of a plug *p* is shown touching the test-piece of switch *a*. Since the portion *i* of the metallic circuit is open at switch

b, the circuit-breaker *k* will not interrupt the circuit of telephone *q* when plug *p* is thus touched to the test-piece of switch *a*, as shown. Thus the metallic circuit being in use when a plug *p* connected with a telephone *q* and test-battery is applied to any switch of the line at any other board, no rattling caused by the circuit-breaker *k* will be heard in telephone *q*; hence the operator listening at telephone *q* will know that the line is busy when he hears no rattling in said telephone *q*. In like manner, if the tip or plug *p* be applied to the frame of switch *c* of the ground-circuit as long as the ground-circuit is open, as shown at switch *d*, the portion *n* of said ground-circuit which contains the circuit-breaker *o* being open, the circuit-breaker will have no effect to interrupt the circuit through the telephone *q*, and the operator listening at said telephone *q* by the absence of any rattling in his telephone will know that the ground-line is in use. Thus the same signal indicates "busy," whether the test be applied to the metallic circuit or the ground-circuit.

We will suppose now that the plugs are removed from switches *b* *d*, so that both lines will be free. In this case the tip of plug *p* is touched to the frame or test piece of switch *a*, as shown, and the circuit will be closed through the telephone *q* and circuit-breaker *k*, and the interruptions of the circuit caused by circuit-breaker *k* will cause a rattling, which will indicate that the line is free. This circuit may be traced from the ground-plate *r* to the heel of the plug resting thereon, and thence through strand *s* of the cord through the loop-switch and test-battery and telephone *q*, as shown, to the tip of the plug *p*, and thence to the frame of switch *a*, and thence through line *i* and the circuit-breaker *k* to branch *h* of the metallic circuit, and over said branch *h* to the subscriber's switch-lever *g*, and thence through the bell and generator to ground *f* at the subscriber's station. Thus when no plug is inserted in any switch of the line and a plug *p* is applied to the test-plate of any switch upon either of the boards the circuit-breaker *k* will be included in circuit with the test-battery and telephone *q* and the operator will know by the rattling caused in his telephone by the interruption of the circuit that the line is free, and in like manner when a test is made at one of the switches of the ground-line *m* a rattling will be heard in the operator's telephone if said ground-line is not busy.

We will suppose the plug removed from switch *d* and the tip of plug *p* resting upon the test-plate of switch *c*. In such case the circuit would be traced as before, from ground-plate *r* through the strand *s* of the flexible cord, the telephone *q* and test-battery being looped in said strand *s* to the frame of switch *c*, and by test branch *n* connected with said frame through the circuit-breaker *o*, and thence to line *m* and to ground at the subscriber's station. Since resistance *e* is in-

cluded in the ground branch at the subscriber's station, current will be shunted through the circuit-breaker *k*, and thus the circuit of the test-battery through the telephone *q* will be interrupted, causing a rattling in the telephone, and the operator listening at telephone *q* will know by said rattling that the line is free. Thus by the rattling in the telephone the operator will know that the line is free, whether he be testing a metallic or a ground circuit.

Having thus described my invention, I claim as new and desire to secure by Letters Patent—

15 1. A telephone-line connected with ground at the subscriber's station and extending through a switch on each of two or more switch-boards, a circuit-breaker, and a connection from said circuit-breaker to the frames 20 or test-pieces of the switches of the line, in combination with a branch circuit to ground at each board, including a telephone and test

battery, whereby a test may be made at any board to determine whether the line is in use or connected at any other board.

2. In a multiple switch-board system, the circuit connecting together the springs of several spring-jacks, one upon each board, another circuit connecting together the test-pieces of the said jacks, and a constantly-vibrating circuit-breaker included in the circuit between the frames of the jacks, in combination with a telephone and test-battery, whereby an operator may determine by closing the said telephone to one of the test-pieces whether the line is open at any one of the spring-jack switches.

In witness whereof I hereunto subscribe my name this 16th day of November, A. D. 1886.

CHARLES E. SCRIBNER.
